UNITED STATES PATENT OFFICE.

KARL WIESER, OF BREDENEY, GERMANY, ASSIGNOR TO FRIED. KRUPP AKTIEN-
GESELLSCHAFT, OF ESSEN-ON-THE-RUHR, GERMANY.

IMPACT-FUSE.

1,063,095.

Specification of Letters Patent. Patented May 27, 1913.

Application filed October 10, 1910. Serial No. 586,273.

To all whom it may concern:

Be it known that I, KARL WIESER, a subject of the Emperor of Germany, and a resident of Bredeney, Germany, have invented 5 certain new and useful Improvements in Impact-Fuses, of which the following is a specification.

This invention relates to impact fuses having a safety device for preventing a premature ignition that is automatically thrown out after the gun has been fired; the object of the invention being to provide means increasing the safety of this kind of fuse. This object is attained, in accordance 15 with the present invention, by means of a gear, operated by spring-power and set in motion automatically in firing the gun, in order to throw out the safety device.

An impact fuse in accordance with this 20 invention is particularly suitable for use in double or combination fuses, that have a mechanical time fuse driven by clock-work. In such fuses, the clock-work of the time fuse will also be used for throwing out the 25 safety device of the impact fuse.

Two different embodiments of the invention are shown in the drawings, both being intended as constituent parts of a double or combination fuse of the above mentioned 30 kind.

The first embodiment is illustrated in Figs. 1 to 6, showing in Fig. 1, a longitudinal section through the combination fuse (some of the details of the mechanical time 35 fuse are shown in full lines); Figs. 2 and 3 are sectional views on the line 2—2 of Fig. 1 with some of the parts in different positions; Fig. 4 is a longitudinal section corresponding to Fig. 1, with some of the parts 40 in different positions; Fig. 5 is a section at line 5—5, Fig. 1, seen from the left; Fig. 5^a is a sectional view similar to Fig. 5, but in larger scale and showing the clockwork in detail. Fig. 6 is a section at line 6—6 of Fig. 45 Fig. 1, with the impact-charge removed; Fig. 7 is a longitudinal section illustrating the second embodiment of this invention; Fig. 8 is a sectional view on the line 8—8 of Fig. 7; Fig. 9 is a view corresponding to Fig. 7, but with some of the details in different 50 positions; Fig. 10 is a sectional view on the line 10—10 of Fig. 9; Fig. 11 is an enlarged detail sectional view on the line 11—11 of Fig. 7.

I will now describe the first embodiment 55 illustrated in Figs. 1 to 6.

The assembly and operation of a mechanical time fuse having a housing A and a hollow screw-shank a¹ screwed into the shell-body, have been substantially described in 60 United States Patents Nos. 728,151; 854,977 and 886,564 and need therefore no further explanation here. Suffice it to say, that the time fuse is provided with a clockwork T, driven by a spring R (Fig. 5^a), which clock-work is held in check, during the transporting state of the fuse, by means of an arm K⁴ carried by the main-spindle K and arrested at its outer end by the stop bolt t¹. This stop bolt will, influenced by the inertia 65 in firing the projectile, move into a position in which it will release the arm K⁴, by which movement the clockwork is released. In firing, therefore, the clockwork is automatically set in motion and with it the main 70 spindle.

Most of the gearing of the impact fuse is inclosed in the housing B which is placed in the hollow chamber of the shank a¹. This housing forms a narrow box, open on top 80 and resting with its narrow sides on an inner flange a² of the hollow shank a¹. The bottom of the housing B is formed in the manner indicated in Fig. 1, in order to get the space for the fulminate C. The housing B, resting with its upper side against a partition a⁵ in the housing A, is secured by means of a plate a³ held by screws a⁴ to the flange a², this plate at the same time closing the bottom of the housing A for the mechanical 85 time fuse. The open space formed between the outside of the wall of the housing B, the inside of the wall of the hollow shank a¹, and the inclosing plate a³ forming the bottom, is filled with the impact charge S 90 of the time fuse. The impact charge S connects through passages b¹ (Fig. 5) with the fulminate C, from which a passage U leads to the bursting charge of the projectile. 95

On the raised part of the bottom of the 100 housing B, a flat spring D is secured, which carries the firing point d¹. In the transporting state of the fuse, this spring rests with its free bent down end on a lip e¹ of a lever E which is pivotally carried in the 105 housing B on two journals e² (Fig. 6). The lever E rests with its free end on a bolt b², screwed into the bottom of the housing B.

The lip e^1 is situated between the pivot axis of the lever E and the bolt b^2 , so that the spring will press the lever against the bolt b^2 .

- 5 To secure the lever E from prematurely raising itself from the bolt b^2 , during transportation of the fuse, a bolt F is provided, which is movably carried in the partition a^5 of the housing A as well as in the bottom-plate G and top plate H of the mechanical time fuse. The bolt F is under the influence of a spring f^1 which with one end, rests on the bottom plate G of the mechanical time fuse, and with the other end against 10 a collar f^2 situated above this plate on the bolt F; in such a manner that the spring under compression, has a tendency to raise the bolt from the lever E. This is prevented, in the transporting state of the fuse 15 by means of a sear J, which is pivotally mounted on the top plate H, against which the upper end of the bolt F is being pressed by the spring f^1 . The sear J is in its turn locked in the transporting state of the fuse, 20 to a disk K¹, secured to the main spindle K of the clock-work of the mechanical time fuse, the spindle turning in the direction of the arrow x (Fig. 2). For this purpose, the sear is provided with a lip i^1 which interlocks with the recess k^2 of the disk K¹. 25 The sear J has a key-hole-shaped opening i^2 , which is so arranged and shaped, that the bolt F may run through the circular part of the opening i^2 when the sear J stands 30 in the position shown in Fig. 4. When the bolt F projects through the opening i^2 , the collar f^2 rests against the lower face of the top plate H of the mechanical time fuse. In this position, the narrow neck f^3 of the 35 bolt F is opposite the narrow slit of the opening i^2 , so that, by a continued outward rotation of the sear J, the slit of the opening i^2 will enter over the neck f^3 of the bolt F and thus lock the bolt in its pushed out position (Figs. 3 and 4).

In firing, the clock-work of the mechanical time fuse is set in motion and the disk K¹ will begin to revolve in the direction of the arrow x (Fig. 2) whereby the lip i^1 of the sear J is released from the recess k^2 of the disk K¹. As soon as the sear is free it will swing outward under the action of the centrifugal force occasioned by the rotation of the projectile. Then when the 50 circular part of the opening i^2 stands right above the head of the bolt F, the latter will be pushed through the opening of the sear J by the force of the spring f^1 , and by the continued swinging of the sear outward, 55 occasioned by the centrifugal force, the narrow slit in the opening i^2 will engage the neck f^3 of the bolt F, thereby locking the latter. The impact fuse is now cocked.

The time between the firing of the gun 60 and the cocking of the fuse depends on the

length of the lip i^1 or the depth of the recess k^2 and may easily be regulated to suit different requirements by choosing these measurements accordingly.

On impact, the lever E is swung forward 70 by its inertia, whereby the spring D slips off the lip e^1 of the lever E and drives the firing point ϕ^1 into the fulminate C (Fig. 4).

The second embodiment, illustrated in Figs. 7 to 11, differs from the first one, by 75 having still another separate safety device, which, in case the firing spring D¹ should break where it is bent, will prevent the ignition of the fulminate C¹. The safety arrangement for the releasing lever E¹ is also 80 somewhat changed.

As safety against ignition of the fulminate C¹, in case the spring D¹ should break, a slide M is provided, which, during the transporting state of the fuse, has such 85 a position, that it covers the fulminate C¹ (see Figs. 7, 8 and 11). Resting with its surface m^2 , when in the above mentioned position, against the raised part of the bottom of the housing B¹, under the influence 90 of two springs m^2 (see Fig. 11), the slide M is radially movable on the bottom of the housing B¹, being held in position by the head of a screw N, the shank of which runs through a slit m^1 of the slide. The head of 95 the screw N supports at the time the lever E¹. When the centrifugal force has brought the slide into its outermost position as represented in Fig. 9, the fulminate C¹ will be uncovered. Simultaneously, the opening m^4 100 in the slide will take such a position that it will allow the bent down end of the spring D¹ to run through.

In order to secure the slide M, during the transporting state of the fuse, in such a 105 position that it covers the fulminate the following arrangement is provided.

The slide M has an arm m^5 , which, in the transporting position of the slide, lies above and engages the lever E¹. The arm 110 rests against a pin P, eccentrically carried on the bottom side of a disk p¹, which can turn in the partition a^6 of the housing A¹. The disk p¹ is secured to the spindle p², which is pivoted in the plates G¹ and H¹ of 115 the mechanical time fuse; and through this spindle, the disk p¹ is fixedly connected to a sear J¹, which is fastened to the upper end of the spindle p² above the top plate H¹. During the transportation state of the fuse, 120 the sear J¹ is locked to the disk K², which is attached to the main spindle K³ of the clock-work of the mechanical time fuse, in the same manner as already has been described in the first embodiment of the invention. 125 Through the locking of the sear J¹, the pin P is also held fast. This prevents consequently any outward movement of the slide M from its position shown in Figs. 7 and 8. The pin P is in this position, situated above 130

the lever E^1 and fulfils in consequence, the same function as the bolt F in the first embodiment, which has for its object to secure the lever E^1 against its being raised from the screw N .

5 The release of the slide M and the lever E^1 will follow on the turning of the disk p^1 . The pin P will then take the position indicated in Fig. 9, where it lies outside of the path of the lever E^1 , permitting an outward movement of the slide M , whereby the arm m^5 also will get out of the path of lever E^1 .

10 As soon after the firing, as the parts J^1 and K^2 have been unlocked, the sear J^1 swings outward actuated by the centrifugal force developed by the rotation of the projectile; at the same time turning the disk p^1 by means of the spindle p^2 . The pin P will then be swung over to the position indicated in Fig. 9, so that the slide M and the lever E^1 will be free. The slide M now moves outward, actuated by the centrifugal force to the position indicated in Fig. 9, leaving the fulminate C^1 uncovered 20 and placing the opening m^4 underneath the bent-down end of the spring D^1 . The fuse is now cocked. On impact, the lever E^1 is swung forward by its inertia. The spring D^1 will then slip off the lip e^3 , driving the 25 firing pin d^3 into the fulminate C^1 .

30 As the throwing out of the safety device of the impact fuse in both of the above described embodiments of the invention is caused by the clock-work of the mechanical time fuse, the moment of the cocking of the impact fuse is consequently determined by equal accuracy with that, by which the mechanical time fuse is distinguished.

I claim:—

40 1. In an impact fuse, the combination with a pellet, of a movable part causing the ignition of the pellet on impact, a safety device for said movable part, and a spring-actuated clockwork for controlling the disengagement of the safety device, said clockwork being automatically started by the firing of the gun.

45 2. In an impact fuse, the combination with a pellet; of a movable part, causing the ignition of the pellet on impact; means for holding said movable part in inoperative position until the moment of impact; a safety device controlling said holding means, a spring actuated clockwork started by the firing of the gun, said clockwork adapted to release said safety device.

50 3. In an impact fuse, the combination with a pellet; of a spring-controlled firing point for igniting said pellet; means for holding said firing point in inoperative position until the moment of impact; a safety device controlling said holding means; a spring actuated clockwork started by the

firing of the gun, said clockwork adapted to release said safety device.

65

4. In an impact fuse, the combination with a pellet; of a spring-controlled firing point for igniting said pellet; a swinging lever keeping the spring cocked and holding the firing point in inoperative position until the moment of impact, when said lever releases the firing spring as the lever swings, influenced by the inertia; a safety device controlling said swinging lever; a spring actuated clockwork started by the firing of the gun cooperating with said safety device.

5. In an impact fuse, the combination with a pellet; of a spring-controlled firing point for igniting said pellet; a swinging lever keeping the spring cocked and holding the firing point in inoperative position until the moment of impact, when said lever releases the firing spring as the lever swings influenced by the inertia; a safety device comprising a bolt, adapted to prevent the swinging of said lever, a baffle plate restraining said bolt, and a latch plate normally interlocking with said baffle plate; a spring actuated clockwork, started on the firing of the gun, said latch plate being rigidly mounted on a rotary part of the clockwork and adapted to release said baffle plate after starting of the clockwork.

6. In an impact fuse, the combination of a pellet, a firing pin for igniting said pellet, a movable part causing the entrance of said firing pin into the pellet on impact, a safety device for said movable part, a spring-actuated clockwork for controlling the disengagement of the safety device, said clockwork being automatically started by the firing of the gun, and a movable cover interposed between the pellet and the firing pin, said cover normally being interlocked by said safety device in a position in which it prevents the entrance of the firing pin into the pellet and adapted to automatically move out of that position, when the safety device is disengaged.

7. In a combined impact and mechanical time fuse, the combination with a pellet, of a movable part causing the ignition of the pellet on impact, a safety device for said movable part, and a spring actuated clockwork for driving the mechanical time fuse and controlling the disengagement of the safety device, said clockwork being automatically started by the firing of the gun.

The foregoing specification signed at Barmen, Germany, this 20th day of September, 1910.

KARL WIESER. [L.S.]

In presence of—

ALFRED HENKEL,
WALTER VONNEGUT.
